UNITED STATES PATENT OFFICE

ROY T. WATTS, OF BALTIMORE, MARYLAND, AND JOHN J. CARR, OF SYRACUSE, NEW YORK, ASSIGNORS, BY MESNE ASSIGNMENTS, TO WILLIAM W. VARNEY, OF BALTIMORE, MARYLAND

ACOUSTIC VIBRATOR

Application filed July 24, 1926. Serial No. 124,622.

The object of our invention is the providing of an improved acoustic vibrator.

A further object of our invention is the providing of an improved acoustic vibrator of the portable type provided with means of folding so that the same may be carried flat and formed into a curved position when in use.

A further object of our invention is providing an improved means of folding a portable acoustic vibrator whereby the edge near the fold may assume substantially the same curvature as other parts of the vibrator when in use.

15 A further object of our invention is providing an improved collapsible cone vibrator having means of substantially forming the same into a cone and the securing thereof for use.

20 Acoustic vibrator, the subject of this specification, is especially adapted for "phonographic" and "loud speaker" use, but is equally well adapted for reception as well as production. The means provided for accomplishing the objects of this invention are 25 equally applicable for forming what is known as a "megaphone" where portability may be had in flat form.

With the foregoing and other objects in view, our invention consists of the novel construction, combination and arrangement of parts as hereinafter specifically described and illustrated in the accompanying drawings, wherein is shown the preferred embodiment 35 of our invention, but it is understood that changes, variations and modifications may be resorted to which come within the scope of the claims hereunto appended.

In the drawings of the herein described embodiment of our invention Figure 1 is a plan view of the vibrator unfolded or opened out ready to be curved and secured in position to form a cone; Figure 2 is a sectional view taken through 2-2 of Figure 1, looking in the direction of the arrows and Figure 3 is a sectional view taken through 3-3 of Fig. 1, looking in the direction of the arrows.

Similar numerals refer to similar parts throughout the several views.

50 1 is an element of the cone provided with

an extended or lip portion 2. 3 is an element of the cone not provided with the lip portion 2. These elements 1 and 3 may be formed of any suitable flexible material for curving into working shape. We have found paper very 55 successful as it is light and easily handled as well as being cheap of construction. The paper may be treated, sized or coated as desired for durability or otherwise. We have found plain uncoated paper very successful 60 but where waterproofness is desired where the vibrator is to be used in the open weather, we have found that a suitable coating of a waterproofing character is desirable, or flexible varnish.

65 On either element 1 or 3 may be secured, securing clips 4. In the drawing they are shown attached to element 3, and are secured thereto by means of eyelets 5. In the drawing we have shown two sets of clips "4", between which the element 1 is forced and clamped thereby. One clip only may be used with success. We have found two met all requirements in the practice of a small phonograph. More clips may be used, if desired. These clips are usually made of metal, but may be made of any resilient substance tending to maintain its shape or 70 springlike condition for clamping purposes. Elements 1, 1 and 3 are hinged together as 75 shown in Figure 2, preferably by a fabric hinge 6. In this case a piece of cloth pasted over the edge of element 3 and unto element 1 some distance back from extended or lip portion 2 of element 1 and likewise the joining of elements 1 and 1. In collapsing the 80 elements fold on themselves at junction of the hinge 6 and when folded out and curved with lip portion 2 curves and forces the edge to curve also, thus producing substantial and 85 symmetrical cone when secured by means of clips 4 unto edge of element 1.

90 The cones as assembled, formed as above suggested, are clamped or secured to the vibrating mechanisms, forming no part of this 95 invention, there being a slight opening 7 at the small end or apex through which the securing means is inserted. While, technically, the cone is not a perfect geometrical cone having a perfect apex, but a truncated 100

cone, the apex being so small; however, that we call it and treat it as a cone.

Having thus described our invention, what we claim, and desire to secure by Letters Patent is:—

- 5 1. A collapsible sound reproducing diaphragm comprising a plurality of flexible elements, hinged together so as to form an extended unit when opened out and means of securing the adjacent free edges to form a curved structure.
- 10 2. A collapsible sound reproducing diaphragm comprising a plurality of flexible elements, hinged together so as to form an extended unit when opened out and means of securing the adjacent free edges to form a curved structure, said hinged portion consisting of joining adjacent members with a common fibrous element.
- 15 3. A collapsible sound reproducing diaphragm comprising a plurality of flexible elements, hinged together so as to form an extended unit when opened out and means of securing the adjacent free edges to form a curved structure, said hinged portion consisting of lapping one adjacent element over the other so that its free edge may rest within said other element at all times when said elements are inwardly curved with reference to
- 20 30 said overlapping element.
- 35 4. A collapsible sound reproducing diaphragm having a plurality of flexible elements hinged together, a hinge comprising means of securing the edge of one element to another element at a predetermined distance from its edge.
- 40 5. A collapsible sound reproducing diaphragm having a plurality of flexible elements hinged together, a hinge comprising means of securing the edge of one element to another element at a predetermined distance from its edge, consisting of a cloth strip secured to said elements at said point.

ROY T. WATTS.

JOHN J. CARR.
